To all whom it may concern:

Be it known that I, Richard J. Ohno, a citizen of the United States, residing in Branford, in the county of New Haven and State of Connecticut, have invented a new, original, and ornamental Design for a Door Knob, of which the following is a specification, reference being had to the accompanying drawing, forming part thereof, in which:

Fig. 1 is a side elevational view of a door knob embodying my new design;

Fig. 2 is a top plan view;

Fig. 3 is a bottom plan view; and

Fig. 4 is a side elevational view partly in section on line 4—4 of Fig. 2.

I claim:

The ornamental design for a door knob, substantially as shown.
